UNITED STATES PATENT OFFICE.

SAMUEL W. SAXTON, OF NEW YORK, N. Y.

HOLDER FOR EYEGLASSES.

SPECIFICATION forming part of Letters Patent No. 392,367, dated November 6, 1888.

Application filed May 14, 1888. Serial No. 273,739. (No model.)

To all whom it may concern:

Be it known that I, SAMUEL W. SAXTON, of New York, in the county and State of New York, have invented a certain new and useful Improvement in Holders for Eyeglasses, of which the following is a specification.

I will describe an eyeglass-holder embodying my improvement, and then point out the various novel features in claims.

10 In the accompanying drawings, Figure 1 is a side view of an eyeglass-holder embodying my improvement. In this figure the device is represented as being inserted in the fabric of a garment. Fig. 2 is another side view of 15 the holder. In this figure the device is shown as completely attached to the fabric of a garment. Fig. 3 is a front view of the holder. Fig. 4 is a sectional view, the section being taken as indicated by the dotted line x x , 20 Fig. 3.

Similar letters of reference designate corresponding parts in all the figures.

A designates a bar or base-piece.

B designates a hook secured at the lower 25 end to the bar or base-piece A and extended upwardly. Near the free end this hook extends close to the bar or base piece. The loop of a pair of eyeglasses may be slipped over the free end of the hook. It will then be prevented 30 from being slipped off without considerable force being exerted, because of the extension of the free end portion of the hook close to the bar or base-piece. The hook B therefore constitutes a retaining device for an eyeglass.

35 The bar or base-piece may be made of any desired shape. In effect it is merely the shank of the hook, and is herein termed a "bar" or "base-piece" merely to distinguish it from the hook proper.

40 C designates a pin, shown as rigidly secured to the upper end of the bar or base-piece and extended rearwardly and downwardly therefrom. Its free end is bent slightly rearward as compared with its main portion.

45 D designates a pin which at one end extends into a cavity arranged longitudinally in the lower portion of the bar or base-piece. Below the bar or base-piece this pin D is extended rearwardly and upwardly. At the free 50 end it extends slightly rearwardly. The pin D is capable of a sliding movement lengthwise

of the bar or base-piece. A spring, E, arranged within the cavity of the bar or base-piece and between the bottom thereof and a head upon the end of the pin which fits within the cavity, 55 normally maintains the pin in the position in which it is shown in Fig. 2. The pin D can be drawn downwardly or the bar or base-piece upwardly, so that this pin and the bar or base-piece will occupy the relation illustrated in 60 Fig. 1.

The pin D is so bent at the free end that when it occupies its normal position, as shown in Fig. 2, its free end will extend rearwardly beyond the free end of the pin C. This relation between the free ends of the two pins is 65 of importance.

The end of the pin D which is within the cavity of the bar or base-piece may be provided with a head of polygonal form, and the 70 said cavity may be polygonal, so as to prevent the pin from rotating axially with respect to the bar or base-piece. The spring E may be a spiral spring coiled around the pin D between its head and the bottom of the cavity in 75 the bar or base-piece.

I have shown the bow of the hook as provided with an eye, b, to which a chain or cord attached to an eyeglass or pair of eyeglasses 80 may be secured.

It will be seen that the hook B and the pins C D are approximately in line, or, in other words, approximately in the same plane.

The device which I have described is applied to the fabric of a garment by taking the 85 device in the hand with the free end of the hook uppermost and moving it upwardly with the point of the pin D inserted in the fabric of the garment. The device will be moved upwardly far enough to slide the bar or base-piece lengthwise of a portion of the pin D which is within the cavity in the bar or base-piece. When the bar or base-piece is slid up far enough, the device is pressed backwardly, so that the free end or point of the pin C may 90 be inserted in the fabric of the garment. Then the device is either let go or pressed downwardly, so as to cause the pin C to be inserted into the fabric of the garment up to the bent portion. During this downward movement 95 of the device the bar or base-piece will slide downwardly along the portion of the pin D 100

which is within it. The two pins will then securely fasten the device to the fabric of the garment.

It is advantageous to have that pin which is rigidly connected to the bar or base-piece located at the upper end of the latter, because the strains transmitted to the device will be downwardly and will not tend to disengage the device when they will be transmitted to the pin which is rigidly secured to the bar or base-piece. As there will be little liability of strains in an upward direction being transmitted to the bar or base-piece, it is desirable to have the pin, which has a yielding connection with the bar or base-piece, located at the lower end of the latter.

It is advantageous to extend the free end or point of the pin D rearward of the free end or point of the pin C, because the latter will not then interfere with the insertion of the point of the pin D into the fabric of a garment. Moreover, the free end or point of the pin D, when extended rearwardly of the free end or point of the pin C, will not be apt to engage with the fabric of the garment when the device is moved upwardly to disengage the pin C from the garment. It will be readily understood that the disengagement of the device from the garment is effected by an upward movement sufficient to disengage the pin C, and subse-

quently by a downward movement serving to disengage the pin D from the fabric of the garment.

What I claim as my invention, and desire to secure by Letters Patent, is—

1. In an eyeglass-holder, the combination, with a bar or base-piece, of a pin rigidly secured to the upper end of the bar or base-piece and extending rearwardly and downwardly, another pin having a sliding connection lengthwise of the bar or base-piece and extending rearwardly and upwardly, a spring for moving the last-mentioned pin in one direction, and a retaining device upon the bar or base-piece, substantially as specified.

2. In an eyeglass-holder, the combination of a bar or base-piece having at the front a hook with its free end extended upwardly, a pin rigidly secured to the upper end of the bar or base-piece and extending rearwardly and downwardly, another pin extending within the bar or base-piece, and a spring within the bar or base-piece and surrounding the pin last named and causing the movement of said pin in one direction, substantially as specified.
